(57) **CLAIM**

The ornamental design for a cover for device mounting structure of helmet, as shown and described.

DESCRIPTION

FIG. 1 is a front, top and right side perspective view of a cover for device mounting structure of helmet showing my new design;

FIG. 2 is a rear, top and right side perspective view thereof; FIG. 3 is a front view thereof;

FIG. 4 is a rear view thereof;

FIG. 5 is a top plan view thereof;

FIG. 6 is a bottom plan view thereof;

FIG. 7 is an enlarged right side view thereof;

FIG. 8 is an enlarged left side view thereof; and,

FIG. 9 is an enlarged cross-sectional view taken along line 9-9 in FIG. 3.

The broken lines illustrate portions of the cover for device mounting structure of helmet that form no part of the claimed design. The dash-dotted lines denote the boundary of the claim and form no part of the claimed design.

1 Claim, 9 Drawing Sheets
